UNITED STATES PATENT OFFICE.

REINHARDT WILLY BECKERT, OF ALSFELD, GERMANY.

TIE FOR BINDING SHEAVES OR THE LIKE.

1,079,098.

Specification of Letters Patent.

Patented Nov. 18, 1913.

Application filed July 31, 1912. Serial No. 712,575.

To all whom it may concern:

Be it known that I, REINHARDT WILLY BECKERT, a subject of the German Emperor, and resident of Alsfeld, Germany, have invented a certain new and useful Improvement in Ties for Binding Sheaves or the like, of which the following is a specification.

This invention relates to a tie for binding sheaves or the like and has as its main feature a fastening device on one end of the rope or the like into which the rope may be inserted and held without requiring to be knotted.

15 The improved tie is illustrated in the accompanying drawings in which—

Figure 1 shows the fastening device in perspective while Fig. 2 is a view illustrating the manner in which the tie surrounds 20 the sheaf or the like.

As shown to one end of a rope A or the like is secured a fastening device B. This fastening device consists of a folded metal blank, the members b, d, of which have 25 orifices e adapted to register with each other and through which the one end of the rope A is passed and then formed into a loop s. Only that portion k of the member d which is provided with the orifice e lies parallel 30 with the member b. The remaining portion of this member is offset to form an inclined rising back part g and an approximately vertical part f giving a wedge shape to the fastening device. In the part g is 35 formed a slot i which tapers toward the edge o and which is continued in the vertical portion f, the width of the slot in the vertical portion being uniform throughout its length. The width of the slot at this part is some- 40 what wider than the diameter of the largest rope or the like which would be used.

In binding the sheaf m, the rope is inserted with its end s' in the slot i, and is automatically held in the tapered portion by 45 reason of the elasticity of the sheaf.

The portion f in conjunction with the portion k prevents the slot i from widening by

separation of the parts of the part g in forcibly inserting the rope and on the other hand prevents the part g being detached 50 from the member b. By this very simple fastening device the binding of sheaves is considerably facilitated.

Having described my invention what I claim is:—

1. A tie device for binding sheaves comprising in combination with a cord, a strip doubled or folded upon itself, one folded portion being continuously flat and straight from its free end to the line of fold and 60 forming a stiffening base for the tie, the other folded portion being inclined away from the base for a portion of its length from the line of fold and then bent toward and having its free end in flat abutting relation with the free end of the base, both of 65 said free ends being perforated to be attached to one end of the cord, and the inclined and bent part being longitudinally split in V-shaped form to wedgingly engage 70 the remaining end of the cord, substantially as described.

2. A tie device for binding sheaves comprising in combination with a cord, a tie composed of a strip doubled or folded upon 75 itself, one folded portion forming a stiffening base for the tie, the other folded portion being inclined away from the base for a portion of its length from the line of fold and then bent toward and having its free 80 end in flat abutting relation with the free end of the base, both of said free ends being perforated for attachment to one end of the cord, and the inclined part being longitudinally split in V-shaped form to wedgingly 85 engage the remaining or free end of the cord, substantially as described.

In testimony whereof I have signed my name to this specification in the presence of two subscribing witnesses.

REINHARDT WILLY BECKERT.
